UNITED STATES PATENT OFFICE.

ROMANO SERAFIN, OF STAFFORD SPRINGS, CONNECTICUT.

PICKER-STICK.

1,279,024.

Specification of Letters Patent. Patented Sept. 17, 1918.

Application filed October 29, 1917. Serial No. 198,939.

To all whom it may concern:

Be it known that I, ROMANO SERAFIN, a citizen of the United States, residing at Stafford Springs, in the county of Tolland and the State of Connecticut, have invented 5 certain new and useful Improvements in Picker-Sticks, of which the following is a specification.

This invention relates to improvements in 10 looms and more particularly to improvement in picker sticks. The invention broadly comprises a rocker member that is pivotally attached to the rear side of the picker stick proper. This member is so constructed 15 and arranged as to impart a gradual or uniform blow to the rear side of the stick, the force of the blow of the rocker member is designed to engage the picker stick over a considerable portion of its length. An ob- 20 ject of the invention is to connect the rocker member to the sweep-stick by means of a lug strap formed of a single or integral part, preferably of malleable iron, whereby the breakage and wear of this part of the 25 mechanism is reduced to a minimum. In the construction of picker sticks at the present time, so far as I am aware, the lug strap is usually made of fabric, leather or other flexible material, resulting in rapid wear 30 and expense in frequent renewals of the same. By constructing the lug strap of malleable iron, it may be easily bent to accommodate picker and sweep sticks of different widths.

Referring to the drawings:

Figure 1 is a side elevational view showing 40 a portion of the loom to which the stick is attached, a portion of the sweep-stick to which the lug strap and rocker member is connected, also showing the casting by means of which the rocker member is adjustably attached to the sweep-stick for varying the travel or throw of the upper end of the stick which engages the shuttle for propelling the same.

Fig. 2 is a horizontal sectional view on the line 2—2 Fig. 1, showing in detail, the construction of the one-piece malleable iron lug strap.

Fig. 3 is a detail view of the casting for 50 adjustably attaching the rocker arm to the stick.

Fig. 4 is a transverse sectional view on the line 4—4 of Fig. 3.

Fig. 5 is a side elevational view of the 55 attaching casting.

Referring to the drawings in detail:

An upright portion of the loom is indicated 1 and the lay rock-shaft and breast beam at 2 and 3 respectively, to which the 60 upright member 1 is attached. The shuttle is shown in the shuttle box in dotted lines at 4. The picker stick proper is indicated at 5 and is pivotally connected at its lower end to the upright member 1 and lay-rock shaft 65 2 by means of the bracket 6. Secured to the stick 5 is a casting 7 by means of the bolt 8. The casting 7 is formed with a serrated edge 9 which engages the outer edge of the stick and the teeth thereof embed themselves in 70 the edge of the stick 5 when the bolt 8 is tightened. The bolt passes through the elongated opening 8'. 10 designates a rocker member that is pivotally connected to the casting 7 by means of the stud 11, on the 75 extension 11'. This member is formed with a curved or cam shaped surface 12 near its lower and pivotal end connection, the purpose of which is to cushion or lessen the force of the blow between the rocker member 80 and the stick when the sweep-stick 13 is operated with the result that a gradual blow is imparted to the picker stick. The rocker member 10 is connected to the sweep-stick 5 by means of the lug strap which comprises 85 an integral one-piece member that is clearly shown in Fig. 2 and includes the side members 14 and 15 and a connecting pivotal portion 16; the inner ends of the side members are formed with openings 17, 18 and 19 90 through which a securing bolt 20 passes and also through the opening in the end of the sweep-stick 13. A portion of the rocker member 10 is removed in order to connect the lug strap thereto. This removed portion 95 comprises a piece 21, which piece, after being removed, is again fitted in place and secured to the rocker member by means of the screws indicated at 22. The inner surface of the rocker member 10 is preferably covered with 100 felt as indicated at 23, for the purpose of lessening the force of the blow imparted by the rocker member to the picker stick. It will be seen from this construction that when the sweep-stick 13 is operated at a 105 high rate of motion the rocker member 10 is moved against the rear edge of the picker stick 5. The cam surface 12 causes the

rocker to gradually engage the rear surface of the stick without imparting a sudden or impulsive blow to the stick, thus lessening the liability of injuring the shuttle or other parts associated therewith.

It will be noticed that the casting 7 which secures the rocker member 10 to the picker stick 5 is formed with a rib 7¹ which extends upward to the portion 11'. The opposite side of the casting 15 is formed with a rib 7² which engages the side of the picker stick 5 whereby the casting 7 is rendered very much stronger and retains its place much better on the stick than it otherwise would.

What I claim is:

1. A picker stick construction comprising in combination with a sweep-stick, a rocker member pivotally connected thereto, the rocker member having a pivotal and adjustable connection with the sweep-stick, a one-piece metallic-lug strap, the inner surface of the rocker-member being curved adjacent its pivotal connection with the picker stick for imparting a gradual blow to the picker stick for the purpose of lessening the force of the blow when the sweep-stick is operated and for engaging the picker stick.

over a considerable part of its surface for the purpose described.

2. In a device of the kind described, a rocker member for engaging the rear outer lower edge of a picker stick and having a long curved surface for engaging the rear side of the picker stick for the purpose of imparting a gradual or varying blow thereto, means for pivotally connecting the rocker member to the picker stick, means for connecting the rocker member to the sweep-stick, said curved surface of the rocker-member being located adjacent the pivotal connection between said member and stick for the purpose described.

3. In a picker stick device, a rocker member pivotally attached to the stick, said member engaging and operating against the stick, the engaging portion being curved to produce a gradual or varying blow action on the stick, an adjustable connection between the stick and rocker member, said member having a removable portion to permit attaching the same to a sweep-stick, all constructed and arranged to produce a gradual blow to the picker stick for the purpose described.

ROMANO SERAFIN.
